CONTROLLER FOR KNITTING MACHINE

Frederick C. Wiesinger, Feasterville, Pa., assignor to Wildman Jacquard Co., Norristown, Pa., a corporation of Pennsylvania

Application July 9, 1957, Serial No. 670,734

8 Claims. (Cl. 66—155)

This invention pertains to controller means for knitting machines which knit through various phases of a cycle and which require changes only at spaced, short intervals in said cycle, and more particularly, to means for arresting the action of certain of the controller parts except when there is need for its function.

It is a general object of the invention to improve the operation of a knitting machine of the type described, to render its action more silent especially when running at higher speeds and to increase the life of controller parts some of which have heretofore become worn rather quickly even though the need for their function has been limited to only a very short part of the complete knitting cycle.

Other objects will become apparent from the following, more detailed disclosure.

Knitting machines such as that of United States Patent 2,082,127 are employed for knitting articles such as sweater blanks, for example, during which the knitting cycle is changed at frequent intervals, for example, to change yarns being fed, to rack the dial, to effect transfer of stitches from one set of needles to another, to change stitch length, knit separation courses, etc. To time these changes and effect them in proper sequence a controller unit such as that of the patent above cited or United States Patent Re. 23,554 may be employed.

The machine itself is preferably provided with two speeds and changes are usually effected at low speed. The knitting is carried on at a higher speed and thus the controller unit is designed to operate at the lower speed, generally speaking, and, if practicable, it would be desirable to stop the function of all its parts at all other times. Of course, cessation of all movement is not possible, but the pattern advance is stopped and thus there is no selecting function completed, but that part of the mechanism by which a selector lever is caused to impart its selection through to other members has continued to operate and at the high speed knitting, wear and noise occasioned have been very annoying.

According to the instant invention, these undesirable characteristics of the prior art are overcome and motion of the controller parts is limited to rotation of certain gears and shafts all of which are balanced and function more or less idly, but at the most do no more than to advance a pattern chain thereby to control the general cycle.

This chain comprised of differentiated links has for one function the control of stopping and starting the drum and pattern and also, according to the invention, effects certain changes which bring about a cessation of movement of several other parts. As will be described in detail, the parts which do continue in operation are incidental to continued operation in properly timed relation to other parts. The mechanism may always be stopped and then restarted in such a way as to bring the controller and pattern into action with all parts properly synchronized.

The invention will be set forth in greater detail by

2

reference to one specific form the mechanism may take as illustrated in the accompanying figures of drawing, wherein:

Fig. 1 is a perspective view showing the invention as applied to a typical knitting machine.

Fig. 2 is a top view of the controller unit.

Fig. 3 is a view similar to Fig. 1 but showing the parts as seen from the opposite side.

Fig. 4 is a right hand end view of the device.

Fig. 5 is a section taken at line 5—5, Fig. 2.

Fig. 6 is a left end view of part of the mechanism.

Fig. 7 is a detail view of certain parts at the left hand side of the device.

Fig. 8 is a section taken at line 8—8, Fig. 2.

Fig. 9 is a vertical section taken at line 9—9, Fig. 6.

Fig. 10 is a section taken at line 10—10, Fig. 6.

Now referring to Figs. 1, 2 and 3, the controller unit is commonly mounted on a bracket 20 bolted to the lower part of a knitting machine frame and comprises 20 among other parts, a slotted guide member generally indicated by numeral 21 within which are guided for vertical movement a plurality of selector bars 22 each of which is urged downwardly by means of one of the springs 23 attached to a hooked or other portion of the bar and also to the outer end of a spring anchoring member 24. As shown more clearly in Fig. 2, the unit also comprises certain frame side members 25 and 26 within which are rotatably mounted several different parts of the device. At the front a shaft 27 is rotatable 30 in appropriate bearings in the forwardly directed frame parts 28 and 29. This shaft has fixed thereon a slotted drum 30 similar to that shown in patents above mentioned and having at its ends sprockets 31 and 32 adapted to maintain properly aligned with the drum a paper or other more or less continuous type of pattern indicated by letter P and having differently disposed groups of perforations 33 punched therein, these perforations aligning with the slots in the drum for a purpose hereinafter to be explained. This drum has sixteen slots 35 and the shaft 27 has carried thereon beyond the bearing 28 a Geneva wheel 34 which with its hub 35 is maintained in an adjustable, fixed position by means of certain devices at 36 well known in the trade since the same form parts of the well known circular Jacquard type knitting machine. The disc 34 has provision for sixteen movements when advanced as will be explained, one movement corresponding to an advance of the drum and pattern throughout one slot or one row of perforations.

40 A plurality of selector levers 37 are pivoted at 38, Figs. 2 and 8, and these levers formed as shown have spring pressed pins 39 adjacent their outer or relatively free ends, the pins being adapted to drop through a perforation and to enter a slot in the drum so that when advanced throughout a selecting movement, the drum will carry selected levers forwardly since each of the levers is slotted as at 39'. These levers are guided within upright dents of a comb as shown so that they are maintained in proper alignment, there being one lever for each of the selector bars 22 and each of these bars is 45 adapted to be engaged by the upper surface of its respective lever whenever that lever is selected and is then moved upwardly to the dot-and-dash line position of Fig. 8.

46 As shown in both Figs. 2 and 8, a rocking lifter bar comprising a transverse bar 40 fixed to the ends of arms 41 and 42 is adapted to be swung about shaft 38 since the said arms are pivoted thereto. The arm 42 also carries an upper follower 43 and a lower follower 44, each of these being engageable by certain cams. The upper follower 43 is engaged on its cam 45 while a complementary cam 46 acts upon follower 44 so that the arms and the transverse bar 40 tied together as a unit, are periodically

swung to and fro so long as all of the mechanism is in operation. This transverse bar 40 is so positioned as shown in Figs. 1, 3 and 8 that if a lever 37 is not selected, the bar upon its upward movement merely swings into a recess or notch in the lever. If the lever is selected, then it is moved a sufficient distance so that the transverse bar 40 engages in front of a downwardly extending tooth 47 on the lever and elevates that lever to the dot-and-dash line position of the figures. The lever then raises its corresponding bar 22 and the selecting function is 10 thereupon completed.

Of course, in operation, the selecting function goes on with the drum and pattern being moved step by step at each of which steps one or more of the levers 37 may be selected and moved rearwardly whereupon those that are selected are immediately engaged by the upwardly moving transverse bar 40 and are elevated to complete their intended function. All of the levers 37 are urged by means of springs 48 toward the front of the unit, that it, in a direction to assume a non-selected position. To 15 make that function positive, an eccentric 49 is continuously rotated in order to press against the rearmost parts of the levers so that no one may stick in position and thereby cause unintended selection of a bar and, of course, the difficulties which would be forthcoming if that should 20 happen.

The swinging arm 42 pivoted on shaft 38 as described has a depending portion 50 in which is set a wire or other arm 51 to which is connected a tensioned spring 52 which normally tends to return the parts to a lowermost position. However, since the cams 45 and 46 are complementary cams there is no need for the spring 52 except that it tends to keep the mechanism biased in the direction of maintaining the follower 43 tightly against cam 45 at all times. That reduces noise and wear.

Now referring to Figs. 2 and 3, a sprocket 53 is mounted at the outer end of a stud shaft 54 fixed in the frame side member 26 which stud shaft also carries several other parts including a large Geneva wheel 55 and a disc 56 separated by a centrally disposed spacing portion 57. A gear 58 is also freely rotatable on stud shaft 54 and is driven by means hereinafter to be described. The sprocket 53, also loose on the stud shaft, is locked to the gear 58 by means of a plunger 59 capable of being withdrawn by the thumb grip 60 but normally spring pressed into position to lock the sprocket in any one of sixteen different angular positions. This sprocket carries chain 61 which is the pattern chain above mentioned and which has normal or low links and also high links 62, these being adapted to affect a follower 63 in a manner and for a purpose hereinafter to be described.

Now having described several shafts and the parts on them, the manner in which these parts are rotated will be explained. The drive is taken from any convenient moving part of the machine proper, here a miter gear 64 fixed to a shaft (not shown) which is connected to the machine ring gear for continuous rotation. This gear 64 meshes with a second miter gear 65 integral with a hub 66 and spur gear 67, these being free to rotate on a stud 68. The gear 67 meshes with an intermediate gear 69 on stud 70 and the latter drives a gear 71 fast to a double width gear 72, both of these being free on a cam shaft 73. The mechanism described to this point has been found in the prior art, but from this point on the drive provides for stopping this cam shaft at high speed operation, but bringing it back in at low speed, that is, when changes are to be effected.

This rotation of gears 71 and 72 may be imparted to shaft 73 through a sliding, dog clutch 74. This clutch has a tooth 75 which is caught by a tooth 76 on gear 72 and is slidably keyed to the shaft by key 77. A second tooth 78 is adapted to be engaged against a fixed tooth 79 which is a part of a plate 80 adjustably bolted to an end member 81 in turn attached to plate 82 ex- 70

tending up from horizontal frame piece 83, Figs. 1, 6, 7, 9 and 10.

The teeth 75 and 76, when engaged (clutch to the right), drive through to shaft 73 at the end of which are keyed cams 45 and 46. When the clutch is moved to the left the drive is broken and the shaft and cams are stopped as tooth 78 contacts that at 79. Thus the parts are positively held against rotation as soon as the drive is discontinued and as there are only single teeth at either end of the clutch, it can only be picked up again in a properly timed relationship. The slots at the plate 80 permit an angular adjustment of the tooth 79 to stop the parts at the proper position.

As shown in Figs. 1, 2, 7 and 9, a shaft 84 has freely rotatable and slideable thereon, a long hub 85 on which are cut two gears 86 and 87 and a flange 88. This hub also mounts a switch cam 89 having a V-shaped point 90. The gear 86 is driven by gear 72 so that the hub 85 rotates continuously. It drives back through gear 87 to a double lengthed gear 91 free on cam shaft 73 and, as seen in Figs. 2 and 7, that drive is carried on through an intermediate gear 92 to a pinion 93 fastened to eccentric shaft 94.

The flange 88 engages within a groove 95 in the dog clutch 74 and endwise movement of the hub 85 effects a similar movement of the dog clutch. Two posts 96 and 97 move vertically in the base or frame member 83. Post 97 is longer and attaches by a hinge pin 98 to a lever 99. A lever 100 is pivoted at 101 and connects by its slotted ends and pins 102 and 103 to the posts so that as one is moved upwardly, the other moves downwardly and vice versa. These serve in conjunction with switch cam point 90 to move the hub endwise on its shaft. When post 96 is contacted by this cam the hub 35 and functionally integral parts are moved to the right in the figures and that effects two changes. First a pin 104 set in gear 87 is positioned to act upon the Geneva wheel 34 to advance the drum and pattern one step for each rotation of the hub or clutch 74. Also, the latter is 40 pulled to the right; Fig. 2, and the teeth 75 and 76 engage to start rotation of the cam shaft 73 and thus the action of the lifter bar 40. The eccentric 49 is rotated at all times anyway.

Since the shaft 94 is thus continuously rotated, it serves as a crossdrive to parts at the opposite side of the unit. At that end of the shaft a disk 105 carrying a pin 106 is fixed. That pin steps Geneva wheel 55 ahead one notch at each revolution of the disk. Then that wheel through disk 56 and a pin 107 advances a Geneva wheel 108 free on shaft 94 and also integral with a gear 109. The latter meshes with and drives large gear 58 and, of course, the sprocket 53 to advance the chain.

It is to be understood that each Geneva wheel and its driver are constructed as usual so that the wheel locks when not being advanced.

The chain links act upon a follower 63, Figs. 2, 3 and 4, which through arm 110 pivoted at 111 in bracket 112, acts on a link 113 to raise or lower an arm 114. Link 113 is connected at 115 to arm 110 and at 116 to arm 114.

This arm 114 has a notched end which bears under the adjacent end of the lever 99, Figs. 3 and 4. A spring 117 pulls these parts downwardly toward a stop screw 118 by which an adjustment may be made.

This arm 114 also affects a switch 119 and other parts to change from high to low speed and vice versa.

When on low links of the chain, the machine is running at high speed and post 97 is elevated. That means that hub 85 is to the left and clutch 74 disengaged. The drum, pattern, cams 45 and 46 are all idle or stationary and the selector levers 37 are, of course, not moved at all. Thus the only moving parts are those which merely rotate and are largely needed to advance the chain 61 to maintain the cyclic changes at the controller. These all

rotate smoothly and do not involve much by way of noise or avoidable wear.

At a high link on the chain the follower 63 is lifted and the machine drive is changed to slow speed. Also the post 96 rises and shifts the hub to the right. Pin 104 then starts the periodic advance of the drum and pattern. At the same time clutch 74 moves to the right and the teeth 75 and 76 pick up the shaft and cam drive where left so that the bar 40 may elevate a lever or levers 37 which are selected at each step. Corresponding bars 22 are also raised to perform a known function and are later to be released in known manner.

The drum and pattern are timed to advance just before the levers have been lowered enough for their pins to strike the pattern.

When the change has been completed, the follower drops from a high link and the parts change to their high speed relationship. Of course, this cycle may be repeated as often as is necessary for the completion of a knitted article.

The gear ratios, number of levers and bars, the number of slots in a drum and for each Geneva motion may be altered to suit each individual situation. The extent and makeup of a pattern card and of the chain 61 are, of course, variable to a great extent and may be set up according to the particular cycle of knitting desired to be followed.

While one embodiment of the invention has been disclosed, it is to be understood that the inventive concept may be carried out in a number of ways. This invention is, therefore, not to be limited to the precise details described, but is intended to embrace all variations and modifications thereof falling within the spirit of the invention and the scope of the claims.

I claim:

1. In a controller mechanism for knitting machines, the combination of a slotted drum over which an endless strip pattern having pattern determining indicia is passed, sensing means for reading said indicia and for transmitting the dictates of said pattern to means to be controlled thereby, a means for imparting a step by step movement to the drum and a swinging motion to those sensing means selected at each step, and other means for starting and stopping said drum and for rendering active and inactive the means for imparting said swinging movement in accordance with active and inactive parts of a cycle through which said controller means functions.

2. In a controller mechanism for knitting machines, the combination of a slotted drum over which an endless strip pattern having pattern determining indicia is passed, sensing means for reading said indicia and for transmitting the dictates of said pattern to means to be controlled thereby, a means for imparting a step by step movement to the drum and a cooperating movement of those sensing means which have been selected at each step, and means including a second pattern means for starting and stopping the drum and for rendering active and inactive the sensing means which includes shiftable means adapted to be clutched and declutched in accordance with the active and inactive parts of a cycle through which said controller means functions.

3. In a controller mechanism for knitting machines, the combination of a slotted drum over which an endless strip pattern having pattern determining indicia is passed, sensing means for reading said indicia and for trans-

mitting the dictates of said pattern to means to be controlled thereby, a means for imparting a step by step movement to the drum and a cooperating swinging movement of those sensing means selected at each step, shiftable means for starting and stopping said drum and pattern, and a second means responsive to that for stopping and starting the drum and pattern for rendering active and inactive the means for imparting swinging movement to the sensing means.

10 4. Mechanism as defined in claim 3 wherein said means for swinging said selected sensing means comprises cam and follower means and in which a means for rotating said cam means comprising a clutch movable to two positions in one of which it establishes a driving 15 relationship and in the other of which it locks said cam means against further movement.

5 5. In a controller mechanism for knitting machines, the combination of a slotted drum over which an endless strip pattern having pattern determining indicia is passed, 20 sensing means for reading said indicia and for transmitting the dictates of said pattern to means to be controlled thereby, a means for imparting a step by step movement to the drum and a cooperating swinging movement of those sensing means selected at each step, shiftable means for starting and stopping said drum and pattern, and a second means responsive to that for stopping and starting the drum and pattern for rendering active and inactive the means for imparting swinging movement to the sensing means, said means for starting and 25 stopping the drum and pattern and rendering active and inactive the means to impart swinging movement comprising continuously intermeshed gearing and clutch means capable of engagement in only a single driving relationship.

30 6. In a controller mechanism for knitting machines, the combination of a slotted drum over which an endless strip pattern having pattern determining indicia is passed, sensing means for reading said indicia and for transmitting the dictates of said pattern to means to be controlled thereby, a means for imparting a step by step movement to the drum, a lifter bar and a cam and follower means to impart motion to said lifter bar for raising those sensing means selected at each step, said means for imparting movement to the drum comprising 40 a Geneva mechanism, means to render said Geneva mechanism active and inactive, a clutch through which said cam and follower means is driven, a single tooth connection between said clutch and cam drive means, and a means between said Geneva mechanism drive and clutch for coordinating the action of the two.

45 7. Mechanism as defined in claim 6 wherein a single tooth stop is further provided for stopping and holding said clutch and cam and follower means in a definitely timed relationship between active phases of the cycle.

50 8. Mechanism as defined in claim 6 wherein a pattern means is provided for determining the stopping and starting points of the parts during their cycle.
